Inventor:
Alvah C. Roebuck,
by Robert Burns
Attorney.

UNITED STATES PATENT OFFICE.

ALVAH C. ROEBUCK, OF CHICAGO, ILLINOIS.

LIME-LIGHT FIXTURE.

SPECIFICATION forming part of Letters Patent No. 788,795, dated May 2, 1905.

Application filed May 16, 1904. Serial No. 208,158.

To all whom it may concern:

Be it known that I, ALVAH C. ROEBUCK, a citizen of the United States of America, and a resident of Chicago, in the county of Cook 5 and State of Illinois, have invented certain new and useful Improvements in Lime-Light Fixtures, of which the following is a specification.

The present invention relates to that type 10 of lime-light fixtures in which means is provided for effecting rotary, vertical, and horizontal adjustments of the lime or other like incandescing stick or block with relation to the burner-nozzle; and the present improvement 15 has for its object, first, to provide a simple and efficient structural formation and combination of parts whereby the above-mentioned rotary, vertical, and horizontal adjustments of the incandescing lime or like 20 block with relation to the gas-discharge nozzle or jet is manually attained in a ready and convenient manner; second, to provide a simple and efficient attachment of the jet or nozzle to the supply - trunk of the fixture, 25 whereby a substantial and gas-tight connection is had and which at the same time permits of a ready detachment and replacement of the jet or nozzle in the usual cleaning and like operations, all as will hereinafter more 30 fully appear and be more particularly pointed out in the claims.

In the accompanying drawings, illustrative of the present invention, Figure 1 is a side elevation of the present lime-light fixture. Fig. 2 is a plan view of the same. Fig. 3 is an enlarged detail central section at line *x x*, Fig. 2, illustrating the connection of the nozzle to the supply-trunk. Fig. 4 is a similar view illustrating the adjustable carriage 40 and its connected parts.

Similar numerals of reference indicate like parts in the several views.

Referring to the drawings, 1 and 2 represent the usual pair of parallel tubes, connected at their forward end to the supply trunk or head 3 and provided at their rear ends with counterpart attaching-necks 4 for the usual flexible hose connections by which the different gases employed are supplied to the 45 burner jet or nozzle 5 of the fixture.

6 is a tubular supporting-bracket adapted to fit the usual stationary upright standard by which a lime-light fixture is supported in a vertically-adjustable manner in the lamp-casing of a stereopticon or other like apparatus. 55

7 is a horizontal extension of the bracket 6, formed with guide-sleeves through which the aforesaid pair of tubes 1 and 2 pass and have horizontal adjustment, the parts being 60 secured at the desired adjustment by the usual set-screw 8.

9 is a longitudinal feed-screw turning in a screw-threaded socket in the downward extension 10 of the supporting-bracket 6 aforesaid, so that with a rotation of such screw a positive horizontal movement of the same will take place. At its forward end such screw 9 has operative connection with the carriage, hereinafter described, by means of 65 an enlarged head 11, engaging in a correspondingly-formed recess in a depending extension of said carriage, as shown in Figs. 1 and 4. At its rear end such screw 9 is provided with a hand-wheel 12 for convenient 70 manual operation. In the present improvement the feed-screw 9 is of a tubular form with its tubular bore adapted to receive the operating-shaft of the mechanism by which 75 rotary and vertical movements are imparted to the basket or carrier of the lime blocks, as hereinafter more particularly described.

13 is a carriage having lateral tubular extensions embracing the pair of tubes 1 and 2, so as to be guided horizontally thereon. 85

14 is a vertical screw-threaded rod fitting a screw-threaded orifice in the carriage 13 and provided at its upper end with a basket or holder 15 for the block of lime or other material employed in lime-lights. 90

16 is a bevel-pinion arranged near the lower end of the rod 14 and having operative engagement therewith by means of a radial pin 17, engaging in a longitudinal groove 18 in said rod to afford a connection which will 95 impose rotation in unison upon the pinion and rod and at the same time permit of a vertical rectilinear movement of said rod.

19 is a bevel-pinion meshing with and driving the aforesaid pinion 16. Such pinion 19 100

is carried by a horizontal shaft 20, having its journal-bearing in the bore of the feed-screw 9 aforesaid and as shown in Figs. 1, 2, and 4, with its rear end projecting back of the hand-wheel 12 of said screw and provided with a hand-wheel 21 for convenient manual operation.

The described arrangement of the tubular feed-screw 9 and the shaft 20 is adapted to afford a simple and effective means for attaining the regulation and adjustment of the lime-body with relation to the burner-jet in a very convenient manner to the operator.

Another part of the present invention involves a simple and efficient connection of the jet or nozzle 5 to the supply head or trunk 3 in a manner to permit of a ready detachment and replacement of the said nozzle and at the same time provide a gas-tight joint between the parts when assembled. Such connection comprises a construction as follows: 22 is the central vertical bore of the supply-trunk 3 for the reception of the tubular attaching-neck of the nozzle 5. Such bore is preferably counterbored at its upper and lower ends to form annular bearing-shoulders 23, having a square form in cross-section, as illustrated in Fig. 4. 24 is the tubular attaching-neck of the nozzle or jet 5, which in the present construction is formed with a cone-shaped enlargement 25, where it connects with the body portion of the nozzle, and which cone-shaped enlargement is adapted to bear against the upper shoulder 23 of the aforesaid bore of the supply-trunk to afford a tight joint between the parts. 26 is a headed attaching-screw, the screw-threaded shank of which screws into the screw-threaded lower end of the tubular neck 24 aforesaid. Such screw is formed with a cone-shaped portion between its head and shank, which is adapted to bear against the lower shoulder 23 of the bore aforesaid of the supply-trunk to afford a tight joint at the under side of said trunk.

Having thus fully described my said invention, what I claim as new, and desire to secure by Letters Patent, is—

1. In a lime-light fixture, the combination of a burner-nozzle, a supply-trunk, a pair of horizontal supply-pipes connecting with said trunk, a carriage moving on said pipes, a tubular feed-screw connected to said carriage and adapted to impart horizontal adjustment to the same, a vertical screw moving in said carriage and provided with a lime-block carrier at its upper end, a pair of bevel-gears having operative connection with said screw, an operating-shaft passing through the tubu-

lar feed-screw aforesaid and having operative connection with one of the bevel-gears aforesaid, and hand-wheels at the rear ends of the feed-screw and the operating-shaft for convenient manual rotation of the same, substantially as set forth.

2. In a lime-light fixture, the combination of a supply-trunk formed with a vertical bore ending in an annular and angular rim or shoulder at top, a burner jet or nozzle having an attaching-neck and a conical enlargement at the junction of said neck with the body of the nozzle, the said conical enlargement having bearing on the annular rim or shoulder aforesaid of the vertical bore of the supply-trunk to form a close joint, and means for securing the nozzle in place, substantially as set forth.

3. In a lime-light fixture, the combination of a supply-trunk formed with a vertical bore ending in annular and angular rims or shoulders at top, a burner jet or nozzle having an attaching-neck and a conical enlargement at the junction of said neck with the body of the nozzle, the said conical enlargement having bearing on the upper annular rim or shoulder aforesaid of the vertical bore of the supply-trunk to form a close joint, and a headed attaching-screw screwing into the lower end of the attaching-neck aforesaid, and provided with a conical portion adjacent to its head and having bearing on the lower rim of the vertical bore of the supply-trunk to form a close joint, substantially as set forth.

4. In a lime-light fixture, the combination of a supply-trunk formed with a vertical bore ending at its upper and lower ends in counterbores and at bottom of said counterbores in annular and angular rims or shoulders, a burner jet or nozzle having an attaching-neck and a conical enlargement at the junction of said neck with the body of the nozzle, the said conical enlargement having bearing on the upper annular shoulder aforesaid of the supply-trunk, and a headed attaching-screw screwing into the lower end of the attaching-neck aforesaid, and provided with a conical portion adjacent to its head and having bearing on the lower annular shoulder aforesaid of the supply-trunk, substantially as set forth.

Signed at Chicago, Illinois, this 13th day of May, 1904.

ALVAH C. ROEBUCK.
